INDEX TAB

Henry C. Osborn, Cleveland, Ohio, assignor to
 Multigraph Company, Wilmington, Del., a corporation of Delaware

Application December 14, 1931, Serial No. 580,796

17 Claims. (Cl. 129—16.8)

It is frequently desirable to provide means such as index tabs whereby plates, cards, etc. may be distinguished one from the other due to the position of the tab. This enables address plates, for instance, to be classified either for purposes of ready manual sorting or to enable an address printing machine to distinguish mechanically between the different plates and print only from certain selected plates.

10 It is the general object of my invention to provide such mutual formation of the plate and the index tab that the latter may be readily mounted on the former in any of a number of locations, and may be changed at will from location to location, but while mounted may be shifted into different directional positions. I thus provide a large number of selectable indications dependent not only upon the selection of the general location of the tab, but also on its directional standing at such location.

20 My invention is in the nature of an improvement on the construction shown in Patent No. 1,938,579, granted December 12th, 1933, to my assignee, Multigraph Company, on an application of Clifton Chisholm. That patent shows an address plate having a flat area adjacent the upper edge provided with a number of openings through it, and a tab having a bottom tongue offset into a different plane from the body of the tab so that the tongue may be passed through any of the openings and lie on the front side of the plate while the body of the tab is on the rear of it. That tab has an upper tongue adapted to overhang the beaded edge on the plate which it engages slidably so that the tab may occupy different angular positions in its selected general location. Its body is laterally widened and provided with a number of holes through it which are adapted to selectively coact with projections on the plate to retain the tab against inadvertent displacement.

25 My invention materially simplifies the above described construction. I make the plate with a rearwardly offset portion providing, when the plate is vertical, a horizontal ledge on the back of the plate through which there are openings. This enables me to make the bottom tongue on the tab in the same plane as the body of the tab. Instead of widening the tab and providing it with 30 holes to coact with plate projections, I narrow the tab so that it may readily stand between such projections.

35 I have accordingly simplified the construction of the tab, enabling it to be more cheaply formed and more readily tempered. By extending the

tongue directly through an opening transverse to the plane of the tab, I provide a more efficient pivotal anchorage for the tongue. Thus, the tab, while readily mounted in any of its general locations, or removed therefrom manually whenever desired, may, when located, be readily shifted from the vertical position into an inclined position in either direction. I have, therefore, three indications for each general location of the tab.

40 In the drawing, Fig. 1 is a face view of my address plate equipped with a number of my index tabs occupying various positions thereon; Fig. 2 is a perspective looking from the rear of a portion of the plate with the index tab in vertical position thereon; Fig. 3 is a perspective showing such tab in one of its diagonal positions; Fig. 4 is a cross-section through the tab and plate, as indicated by the line 4—4 in Fig. 2; Fig. 5 is a perspective of the tab alone.

45 As indicated in Figs. 1, 2 and 3, the plate comprises a sheet metal member 10 designed to carry, in any suitable manner, a printing form and preferably also an index card. The plate is provided with a longitudinal rearwardly offset trough-like portion 11 parallel with its upper edge, and through the ledge provided in the top of this offset portion are elongated openings 12. The plate has a row of rearward projections 13 parallel to its upper edge, the projections being equally spaced and each located preferably in line 50 with a space between the openings 12. The edge of the plate is beaded or curled over toward the front, as indicated at 14.

55 My index tab designated 20, as a whole, comprises a stamped metal member comparatively narrow and thin and having its body portion 22 in a single plane. The lower end of the body portion is formed into a narrower portion constituting a downwardly projecting tongue 23. In the intermediate region of the tab it is preferably narrowed by recesses 24 formed at its opposite edges. Formed out of the upper portion of the body is an integral forwardly projecting tongue 26, its sides and lower ends are cut from the body but integrally connected therewith at 60 its upper end. This tongue extends diagonally forward, as shown at 27 in Fig. 4, and is thence curved over toward the body, as shown at 28.

65 When the tab is in place, the tongue 23 occupies any one of the openings 12, and the tongue 26 extends over the beaded upper edge of the tab, as illustrated in Figs. 1 to 4.

70 When my tab is vertical, which may be called its normal position, it stands between two adjacent projections 13, as shown in Fig. 2, and is 55

- retained by these projections against inadvertent displacement. However, when it is desired to switch the tab into either of its angular positions, it is shoved manually by the operator's finger, and thus springs across the projection 13 on that side until the opening 25, from which the tongue 26 is cut, comes into registration with that projection, and then the tab is retained in this position, as illustrated in Fig. 3, and in the left hand portion of Fig. 1. Or, if the tab were swung in the opposite direction, it would come into the position illustrated in the right-hand portion of Fig. 1 and be there retained in a similar manner.
- 15 It will be seen that my tab is adapted for ready mounting in any of the openings 12 shown, and interchangeable at will between them, but when mounted in any opening it may be easily shifted, without disturbing its mounting, into a plurality 20 of positions, a total of three being shown. Accordingly, in this embodiment, the tab may give three times as many indications as there are openings 12. The simplicity of construction of both the plate and the tab will also be noted.
- 25 As heretofore indicated, the plate 10 may carry its printing members and card index, if desired, in any suitable manner. I have shown by way of illustration rows of upstanding buttons 15, connected with the plate by corrugations 16, these corrugations and buttons being adapted to support embossed printing strips (not shown), which have edge flanges extending beneath the overhanging portions of the buttons, as indicated, for instance, in Patent No. 1,438,582. I have 30 shown also upwardly turned lips 17, 18 and 19, which may cooperate with the rolled-over edge 14 to retain an index card overlying the upper part of the plate. However, if desired, the index card may be entirely omitted or carried in another manner, and in place of the individual 35 strips, a single plate, having a number of embossed lines may be mounted on the plate 10, as is well understood.
- I claim:
- 45 1. The combination with a member to be indexed having an offset portion with an opening in one of its offsetting walls, and an index tab having a tongue adapted to occupy said opening and having means slidably engaging an edge of the member to be indexed, and means for holding the tab in a plurality of positions while the tongue is in the said opening.
- 50 2. The combination with a plate having a trough-shaped depression therein to provide a transverse ledge, an opening through said ledge, an index tab having a bottom tongue adapted to occupy said opening, and an upper tongue adapted to overhang the upper edge of the plate, and means carried by the plate to engage the body of the tab and hold it in different positions while its bottom tongue is in said opening.
- 55 3. The combination with a plate to be indexed having an offset portion with a plurality of openings through it, and an index tab having a central tongue in the same plane as the body of the tab and adapted to removably occupy any of said openings, whereby the tab may be readily interchangeable among them, and means for holding the tab in a plurality of positions while the tongue is in the same opening.
- 60 4. The combination with a plate having a trough-shaped depression therein to provide a transverse ledge, a row of openings through said ledge, an index tab having a bottom tongue adapted to occupy any of said openings and provide

a removable pivotal mounting of the tab, and an upper tongue adapted to overhang the upper edge of the plate, and means carried by the plate to engage the body of the tab and hold it in different positions with reference to any opening it occupies.

5. The combination of an address plate having openings through it in a portion offset from the plane of the plate, an index tab having a body and lower tongue in one plane, said tongue 10 being adapted to occupy any of said openings, said tab having an upper tongue adapted to overhang the upper edge of the plate, and a row of projections on the plate adapted to variably engage the tab to hold it in different positions 15 while its lower tongue is in the same opening.

6. The combination of an address plate having openings through it, an index tab having a lower tongue adapted to occupy any of said openings and having an upper tongue adapted to overhang the upper edge of the plate, and a row of projections extending transversely from the plane of the plate, said projections being staggered with reference to the openings whereby when the tab is vertical its edges will be engaged on opposite sides by a pair of projections.

7. The combination of an address plate having a row of openings parallel to one edge, an index tab having a tongue adapted to occupy any of said openings and provide a pivotal mounting 30 for the tab, the tab having means slidably engaging the upper edge of the plate, a row of projections formed on the plate, said tab being recessed on opposite sides to allow it to be retained between adjacent projections.

8. An address plate having a longitudinally offset region to provide a ledge transversely of the plate, openings through said ledge, an index tab in the form of a flat strip of metal having a narrower portion at its lower end in the form of a tongue adapted to occupy any of said openings, said tab having cut out of its body and projecting forwardly a tongue adapted to engage the upper edge of the plate, and a row of projections on the plate adapted to coact either with the 45 edge of the tab, or with the opening through the tab out of which the tongue is cut, according to the position of the tab.

9. The combination of an address plate having a curled-over upper edge, a longitudinal depression in the plate parallel with the upper edge, openings in the upper wall of the trough made by the depression, a series of projections formed on the plate, and an index tab adapted to stand on the back of the plate and having at its lower end a tongue extending through one of the openings in the depression, said tab having also an integral tongue extending intermediately from its body and offset to overhang the upper edge of the address plate, the projections of the address plate being arranged to coact with the edges of the tab, or with the opening from which the tongue is cut out, according to the position of the tab.

10. An index tab, having a flat body portion 65 reduced laterally at its lower end to provide a tongue, a tongue cut out centrally of the body portion and extending away from the body and downwardly, and recesses in the opposite edges of the body.

11. An index tab, comprising a strip of sheet material, the lower portion of which is formed into a tongue in the same plane with the body of the strip above the tongue, a tongue cut out of the body and extending away from the body 75

and downwardly and then curved toward the body, and recesses formed in the opposite edges of the body adjacent the opening out of which the tongue is cut.

5 12. An address plate having a longitudinal depression formed in the plate adjacent the top edge to provide a narrow trough, openings through the top wall of said trough adapted to receive an index tab, a row of projections on the 10 plate between the trough and the top edge, said projections being adapted to coact with index tabs pivotally mounted in the openings in the trough.

13. An address plate, a curled-over top edge, 15 a longitudinal depression formed in the face of the plate parallel with the top edge to provide a narrow rearwardly extending trough, openings through the top wall of said trough on the rear side of the plate proper adapted to receive an 20 index tab, and a row of projections in the rear side of the plate between the trough and the upper edge made by indentations in the front, said projections being adapted to coact with index tabs mounted in the openings in the 25 trough.

14. An index tab comprising a planular strip having a bottom tongue in the plane of the strip and of reduced width and an upper tongue strip cut out from a region of the body wall below the 30 top by an upwardly extending cut of U-shape, the latter tongue being bent away from the plane at an acute angle thereto in the general direction toward the bottom tongue and then curving to have a concavity facing the plane of the 35 body.

15. The combination with an address plate formed to carry a printing surface and having

a row of openings parallel with one edge, of an index tab having a centrally located end tongue adapted to be mounted in any opening, the tab having an upper tongue to embrace the edge of the plate, enabling the tab to swing when mounted, a row of projections on the plate, and an opening in the tab adapted to coact with either of two projections for each mounting of the tab.

16. The combination with an address plate having a rod of openings parallel with its edge, 10 a row of projections between the openings and the edge of the plate, the individual projections registering with the spaces between the openings, and an index tab having a bottom tongue adapted to be inserted in any opening and an 15 intermediately cut-out tongue adapted to engage the upper edge of the plate, the opening through the tab resulting from the cutting out of the intermediate tongue being adapted to embrace either of two projections when the tab is inclined 20 at an angle in either direction from a position at right angles to the upper edge of the plate.

17. A tab having a body portion with a central tongue of less width than the body projecting from the lower end of the body and lying 25 substantially in the general plane of the body, and combined with a plate having an offset portion with an opening at its upper edge through which the tongue may pass into the space provided by the offset, means for normally retaining 30 the tab with the tongue in the offset while allowing the tab to swing into either of two positions either side of a normal to the upper edge of the plate, and interengaging means on the plate and tab to locate the tab in either of such two positions.

HENRY C. OSBORN.
